Finland

Filed Oct. 26, 1960, Ser. No. 65,155

Claims priority, application Finland Oct. 27, 1959
4 Claims. (Cl. 212—3)

The present invention relates to an improved preventer system for loading booms or derricks pivotally connected to a vertical loading mast or a corresponding pole on ships and being topable by the aid of a winch operated topping wire and slewable sidewise by means of two guys. Known booms are arranged according to two main principles, i.e. either movable or coupled. In a movable system the booms are moved during their work as well in vertical as in horizontal direction and are often used single. In a coupled system the booms are unmoved during their operation and used pairwise, whereby two booms are mutually cooperating and arranged beside each other. At coupled booms is as a rule one boom placed over the cargo hold of the ship and the other one projecting sidewise from the ship over the quay. The lifting wire of coupled booms are attached to a mutual cargo hook, by which the lifting wires are cooperating at the handling of the cargo.

The present invention refers especially to a preventer system for coupled booms.

When the cargo is handled by coupled, unmovable booms and the lifting wires of the both booms act upon the cargo, horizontal force components will arise in the lifting wires and cause tensions in the outer guys of each boom. In order to strengthen said outer guys one uses extra ropes or so called preventers. When the slanting position of the booms is to be adjusted the guys and the preventers in earlier known system must be loosened before the top wire may be operated by the topping winch. It is especially frequently necessary to adjust the slanting position of the boom over the cargo hold of the ship in order to reach the different points within the cargo hold. On account of the fact that said boom cannot be topped without an earlier loosening of the guys and preventers this means that the loading work must be interrupted which represents a severe drawback.

It is an object of the present invention to eliminate said disadvantage and make the displacement of the boom over the cargo hold possible by means of the topping winch without being forced earlier to adjust the preventer and the guy that is without being forced to interrupt the loading work. By such an improvement a more efficient use of the topping winch will also be obtained.

The preventer system according to the invention comprises one preventer and one guy for each adjustable boom. The system is mainly characterized thereby that the guy is attached between the boom top and a guy point in such a way as to guide the boom top during the topping operation along a circular path in a plane between the boom and the preventer, for instance parallel to the center line of the ship, and that the preventer, in respect of the guy is arranged on the opposite side of said moving plane of the boom top, whereby the preventer is arranged like two branches running from two separate preventer points to the boom top so that during topping of the boom the one preventer branch will be shortened and the other correspondingly lengthened. Hereby the preventer tries to guide the boom top along an elliptical path. Hereby the boom will get a continuous support in both side directions during its topping movement and neither guy nor preventer will have to be loosened or altered before the displacement of the topped boom.

The invention will be explained more in detail in the

2

following referring to the accompanying drawings, in which:

FIG. 1 illustrates coupled booms with a known preventer system,

5 FIG. 2 illustrates an improved preventer system according to the invention. Since this system is intended for that boom which is arranged over the cargo hold, the other boom projecting over the quay fixed by ordinary guys is not shown in this figure.

10 FIG. 3 illustrates a diagrammatic view of the system of FIG. 2 and more particularly the attachment points of the preventer and the guy in the system of coordinates.

FIGURE 4 is a diagrammatic view of a modification, and

15 FIGURE 5 is a similar diagrammatic view of a further modification.

In the various figures of the drawing the elements corresponding to one another are indicated by the same reference numerals.

20 The boom over the cargo hold is indicated by 12 while the other one of the coupled boom pair, projecting sidewise from the ship side over the quay, see FIG. 1, is indicated by 13. The boom 12 is pivotally connected near 14 to the loading mast 15 and the boom 13 in a corresponding way fixed near 16 to the loading mast 17.

The boom 12 is kept in a slanting position respectively topped by a topping wire 3 manoeuvred by a topping winch 4. The other boom has a corresponding topping wire 18 and a winch 19. The sidewise adjustment and

30 fixing of the booms are effectuated by guys and preventers. The preventer of the boom 12 in FIG. 1 is indicated by 1 and its guys by 2 and 10. The preventer of the boom 13, FIG. 1, is indicated by 8 and its guys by 9 and 11. The cargo 22 is lifted by the wire 23 of the boom 12 and the 35 wire 24 of the boom 13 operated by the winch drums 20 and 21 respectively.

According to the earlier known preventer system illustrated in FIG. 1 both booms are primarily adjusted into a certain wanted position and fixed there by the guys and

40 the preventers. It is not possible to alter the positions of these booms without an earlier loosening of the preventers and the guys. If one wishes to top the boom 12 in order to reach another point inside the cargo hold one must interrupt the loading work, then loosen and adjust the preventer and the guys, then alter the slanting position of the boom 12 by aid of the topping wire 3 and its topping winch 4 and then again fix the preventer and the guys before the loading can be continued over a new point of the cargo hold.

45 50 This tiresome necessity is avoided by the system according to the invention and illustrated in FIG. 2 and indicated in FIG. 3.

According to FIG. 2 the system comprises one preventer

55 57 and one guy 5. In this embodiment the right side of the boom 12 is supported by the guy 5 fixed partly near the top P of the boom 12 and partly at the point C near the ship deck. The opposite side of the boom 12 is supported by the preventer the one end of which being fixed at a point A on a transversal support 26 of the loading mast

60 15 and the other end in a point B near the ship deck. The preventer is drawn over a block 25 near the boom top P, which divides the preventer into two parts 6 and 7. The lower end of the boom 12 being pivotally connected to the loading mast 15 is indicated by D.

65 70 The guy 5 is arranged into such a position that when the boom 12 is topped in vertical direction by aid of the topping wire 3 and the topping winch 4, the top P of the boom will move in a geometrical plane approximately parallel to the longitudinal symmetric line of the ship. It is hereby to observe that the guy 5 needs not to be loosened, displaced or changed during said topping movement of the boom. Neither needs the preventer to be

altered since when changing the position of the boom as mentioned above the one part of the preventer, for instance 6, will be shortened and the other part, for instance 7, correspondingly lengthened running through the block 25.

The fastening points A and B of the preventer in FIG. 2 according to a preferred embodiment of the invention are determined by a certain equation. Hereby attention is paid to the fact that while the boom top P, due to its attachment to the guy 5, will move along a circular path in a plane, the block 25 governed by the preventer 6, 7 will try to guide the boom top along an elliptical path. Consequently the points A and B must be chosen in a way which gives the best possible coincidence between said elliptical and said circular paths. The equation as aforementioned is the following:

$$\frac{d^2}{c^2} = \frac{(R-b)^2 + f^2}{(R-b)^2 + e^2}$$

in which c, b, e and d, b, f represent the x-, y- and z-coordinates for the fastening points respectively in a system of coordinates, where the x—y-plane substantially is the same in which the top of the boom is moving and the z-axis of which approximately corresponds with the straight line through the fastening point C for the guy 5 and the pivot 14 of the boom 12, i.e. the point D. The boom and the guy 5 fastened at the top of the boom move each along the surface of a cone whereby their common bases and axes approximately will coincide with said x—y-plane and z-axis respectively of the system of coordinates. The direction of the y-axis coincides with the projection of the boom on the plane of coordinates, when the boom is in a central position. The length of the projection of the boom on the plane of coordinates is indicated by R. The above mentioned equation is based upon the fact that the position of the common point of both portions 6, 7 of the divided preventer is defined by that ellipse in the x—y-plane which as far as possible connects to the arc of a circle formed by the top of the boom.

By means of this system it is possible with a coupled pair of booms to raise and lower the boom positioned above the loading hold without being forced to adjust the preventer and the guy and nevertheless achieve a sufficient support in horizontal direction. When loading and unloading with coupled booms the load acting upon the preventers indicated by 1 and 8 in FIG. 1 is very big as mentioned above. The inner guys indicated by 2 and 9 in FIG. 1 are only slightly loaded. Therefore a known arrangement of the preventer, which can also be mathematically derived from the present invention, if taking the special case where both the fastening points of the preventer coincide on the z-axis is often unpractical, because the preventer points for obtaining acceptable angles and forces would have to be displaced outside the ship.

The same principle as above explained may also be adapted in such a way that the block at the top of the boom is substituted by blocks at the two fastening points of the divided preventer whereby the preventer ends are fixed at the boom top. Hereby the preventer parts running through the blocks at the preventer points may lead to a special winch drum and operated by this in such a way that when the one preventer part is wound up on the drum the other is unwound. By this arrangement it is possible to operate the topping of the boom by the aid of the preventer. Consequently the conventional topping wire and topping winch can be eliminated.

According to another embodiment the preventer is running from the boom top through the block at the first preventer point directly to the other preventer point block and back to the boom top where it is fixed. This arrangement does not eliminate the topping winch.

The above modifications are described below.

According to the arrangement of FIGURE 4 the preventer is fastened at the top P of the boom 12. Starting from this fixing point it runs as shown at 6 over a block

at the point A at the end of the transversal support 26 of the loading mast 15. From the block at A it continues over a second block at A', a third block at B and returns as shown by 7 to the fixing point P at the boom top. 5 The preventer thus forms a closed loop which moves over said three blocks when the boom is lifted or lowered.

According to FIGURE 5 there is also three blocks at respectively A, A' and B. In addition, a winch drum 27 is arranged, for example, on the loading mast 15. The preventer lines are fixed at P on the top of the boom 12. The one branch 6 of the preventer line runs over the block at A and is wound up on said winch drum 27. The other preventer branch 7 is drawn over the blocks at B and A' and is also wound up on said winch drum 27 but in an opposite direction as to the branch 6 in such a way that when the boom is topped, i.e. lifted or lowered, the winch drum is rotated correspondingly whereby the one preventer line branch is wound up and the other one is unwound from the winch drum, whereby the supporting function of the preventer on the boom is maintained unchanged. It should be observed that the arrangement shown in FIG. 5 makes it possible to operate the topping of the boom by the aid of the winch drum 27. The conventional winch drum 20 does not need to be used at all and can consequently be eliminated.

What I claim is:

1. A preventer system for ship booms pivotally connected to a vertical pole such as a loading mast, said preventer system comprising supporting ropes arranged on both sides of the plane in which the boom top moves when topped, characterized thereby that it has one guy fixed between the boom top and a guy point situated on the line running from the pivot of the boom perpendicularly against said moving plane of the boom top and one preventer attached to the boom top and running therefrom as separate branches to two preventer points on the same side of the movement plane of the boom top, whereby the preventer is attached in such a way to the boom top and to said two preventer points that, when topping the boom, the one preventer branch is shortened and the other correspondingly lengthened so as to make the displacement of the boom possible without loosening or altering the preventer and the guy.

2. A preventer system as explained in claim 1, characterized thereby that the preventer points are defined by the formula:

$$\frac{d^2}{c^2} = \frac{(R-b)^2 + f^2}{(R-b)^2 + e^2}$$

50 in which c, b, e respectively d, b, f are the coordinates in a system the x—y-plane of which coincides substantially with the plane in which the boom top moves and the z-axis substantially coincides with the line connecting the pivot of the boom with the guy point of the guy, and R being the length of the projection of the boom on the plane of the coordinates x and y.

3. A preventer system according to claim 1, in which the preventer is arranged to run as a continuous loop starting from a fixing point at the boom top and through blocks at the two preventer points on the same side of the moving plane of the boom top.

60 4. A preventer system according to claim 3, characterized thereby that the preventer ends led through the preventer point blocks are connected to a winch drum in such a way that the one preventer part is unwound simultaneously as the other part is wound up.
